UNITED STATES PATENT OFFICE.

FERDINAND FIECHTL, OF CHERRYVALE, KANSAS.

VERTICAL ZINC-FURNACE.

1,291,643.

Specification of Letters Patent. Patented Jan. 14, 1919.

Application filed November 2, 1917. Serial No. 199,897.

To all whom it may concern:

Be it known that I, FERDINAND FIECHTL, a citizen of the United States, residing in Cherryvale, Kansas, and whose post-office address is c/o the Edgar Zinc Company, Cherryvale, Kansas, have invented certain new and useful Improvements in Vertical Zinc-Furnaces, of which the following is a specification.

10 The present invention relates to smelting furnaces and is particularly adapted to the reduction of zinc. The chief features of novelty reside in the shape of the retort, which is designed to accelerate the reduction 15 at the lower part of the retort, the means for feeding the charge into the retort without permitting the gases and vapors in the retort to escape during the charging operation, the design and construction of the 20 double arm slag breaker, and the various combinations and constructions shown in the accompanying drawings and set forth in the following specification and claims:

In the drawings in which like parts are 25 referred to by like numerals in the several views:

Figure 1 is a side elevation of a furnace partly broken away embodying certain features of the present invention;

30 Fig. 2 is a transverse sectional view taken on the line 2—2 of Fig. 1;

Fig. 3 is an enlarged plan view of the detachable coupling for joining the charging car and the retort for the charging operation;

Fig. 4 is an enlarged sectional view on the line 4—4 of Fig. 3;

Fig. 5 is an enlarged detail showing the mechanism for operating the feeding rods 40 in the charging car;

Fig. 6 is a perspective view of the improved double arm slag breaker.

In the drawings 1 designates the furnace as a whole, 2 the supporting beams and 45 girders, 3 the cellar below the furnace inclosed by the foundation walls 4 which support the beams and girders 2.

The retorts 5 having condensers 6 luted in to openings in their side walls, are disposed vertically in the furnace and are arranged in adjacent rows to facilitate charging. Longitudinal girders 7 and cross-beams 7^a are carried on top of the furnace and framed into the buck stays as shown 55 and they support the longitudinal rails 8.

on which the charging car 9 travels. Suitable switches not shown, are provided so that the charging car 9 may travel over either row of retorts. The retorts 5 are mounted vertically in the furnace with their lower ends seating in the water jackets 9 which serve to gradually cool the residue or spent charge which accumulates in the lower part of the retorts.

The mouth 10 of each retort is of greater 65 diameter than the throat 11, thus forming a retort of substantially frusto-conical shape. In practice a retort of this shape having a gradually decreasing internal diameter from top to bottom has proven very 70 efficient. The effect of the gradually diminishing sectional area toward the throat of the retort where the heat is concentrated tends to accelerate the reduction of the charge of zinc oxid, furthermore as the 75 charge gradually works toward the bottom and becomes lesser in volume or density due to the combustion of the carbon, no pockets or spaces will be formed, and the tendency of the spent charge to bridge at 80 the bottom will be decreased.

The mouth of each retort is closed by a cover 12 having apertures 13 formed therein which are normally closed by movable plugs 14 and the throat 11 of each retort registers 85 and communicates with a residue chamber 15 formed in the water jacket 9.

The residue chamber 15 is closed at the bottom by a revoluble base 16 which is slidably mounted on the sleeve 17 supported in 90 a bearing 17^a and driven by bevel gearing 18 from the line shaft 19. The base 16 is provided with an integral hub 19^a having an annular groove 20 which coacts with a 95 pin 21 in the hand lever 22.

The hub 19^a of the base 16 has a key-way 23 formed therein and the sleeve 17 carries a key 24 adapted to coact with the key-way 23 upon the downward movement of the lever 22 and base 16. The lever 22 is provided with a suitable latch 25 to normally hold the base 16 in engagement with the seat 26 formed at the lower end of the chamber 15.

A slag breaker 27 is secured to a shaft 105 28 which is slidably splined in the bore of the sleeve 17. This shaft is provided with screw threads adapted to co-act with a suitable stationary nut not shown. As thus constructed it is clear that the rotation of the 110

sleeve 17 will cause the slag breaker 27 to be rotated and also fed axially within the chamber 15.

- 5 The double arm slag breaker 27 as shown in Fig. 6 possesses particular advantages over cutters or breakers previously used in this art. Each breaker 27 comprises a central hub portion 29 having an aperture 30 for the reception of the driving shaft. 10 Arms 31—31 radiate from the hub 29 and have horizontal cutting edges 32 formed thereon. At the extremities of the arms 31—31, wedge shaped blades 33 are formed with vertical cutting edges 34. 15 The slag breaker as thus constructed with two radial arms having both vertical and horizontal cutting edges is very effective, it occupies a minimum amount of space in the residue chamber and is so shaped that it contains no pockets or places for the slag or 20 residue to collect or clog in and thereby impair its effectual operation. The wedge shaped blades are very efficient for breaking, scraping and cutting away the slag and residue, which adheres to the interior walls of the chamber 15.

When it is desired to remove the residue from the chamber 15 the operator depresses the lever 22 which will cause the base 16 to be lowered and cause the key-way 23 to engage the key 24 on the revolving sleeve 17 thereby causing the base 16 to be rapidly rotated. The conical shape of the base 16 and the centrifugal action of the rotation 35 of the same will rapidly remove the residue.

Receiving hoppers 35 provided with fire glass windows 35^a and drop-doors 36 are disposed below the exits of the chambers 15, and are adapted to retain the accumulation 40 of residue until such time as the dump-car 37 is brought into position to receive its contents.

In charging the retorts the car 9 which is of sufficient capacity to give all the retorts 45 in the furnace one charge is employed. This car travels longitudinally along the rows of retorts on the tracks 8, suitable switches being provided to shunt it from one row of retorts to another.

50 The bottom of the car is formed with inclined sides which terminate in a neck 38 on the lower end of which an annular flange 39 is formed. The neck is provided with apertures 40 through which pass the feed- 55 rods 41 which are moved up to permit the charge to pass through the apertures 40 into the retort and are then moved down to press the charge into the retort.

To prevent the escape of gases and vapors 60 from the retort during the charging operation, and also the leakage of charge, the detachable coupling 42 shown in Figs. 3 and 4 is used. This coupling comprises complementary halves 43 and 44 hinged together at 65 45, having ears 46 at their free ends with

apertures 47 formed therein. A coupling pin 48 is used to lock the two halves of the coupling together by passing said pin through the registering apertures 47 after the union has been closed to connect the car 70 with the retort.

To insure a tight seal between the neck of the car and the retort, the union is provided with an annular groove 49 to fit the flange 39 on the bottom of the neck of the 75 charging car and a flange 50 to engage the periphery of the cover 12 of the retort.

The feed rods 41 of the charging car are provided with screw threads which engage similar threads in the bracket 51 carried by 80 the frame of the car 9. Worm gears 52 and 52^a having hubs journaled in the lower part 51^a of the bracket 51 are slidably associated with the rods 41 and are provided with keys 53 which slide freely in key-ways 54 formed 85 in the rods 41. The worm gears 52 and 52^a are driven by worms 53^a and 53^b, secured to the shafts 54 and 54^a. Pulleys 55 and 55^a carried by the shafts 54 and 54^a are connected by a crossed belt 56 thereby driving 90 the rods 41 in opposite directions.

The shaft 54 is driven by a motor 57 and suitable belting as shown in Fig. 1. The motor is provided with a suitable reversing switch to control the operation of the feed 95 rods 41. Both rods 41 are provided with screw threads which progress in the same direction, therefore, it will be manifest that as they are driven in opposite directions by the worm gears 52 and 52^a, one rod will feed 100 up while the other feeds down. When the car is to be moved from one retort to another, the motor is stopped when the bottom of both rods are substantially in the same horizontal plane at which time they 105 will be above the cover 12.

In operation the charging car 9 is filled from a suitable over head hopper with a sufficient quantity of charge for all the retorts in the furnace, the car is then moved along 110 the tracks 8 into register with the first retort in the row, the plugs 14 are removed from the cover and the coupling 42 is manually connected to the retort and the neck of the car and the charge is then pressed into the 115 retort by the rods 41 driven by the motor 57 and gearing above described. The direction of rotation of the motor 57 is then reversed to withdraw both rods 41 from the retort and the car is moved to the next retort to be charged whereupon the above operation is repeated.

The retorts may be intermittently charged at intervals as frequently as requirements demand. In practice each intermittent charge represents about one half a cubic foot 125 in volume per condenser, and the charging is done at two hour intervals thereby giving a capacity of six cubic feet per day of 24 hours.

From the above it will be manifest that a furnace of this construction can be operated continuously, the charge being conveniently fed to the retorts at frequent intervals and the residue being periodically removed by the efficient devices hereinbefore described.

While I have described in considerable detail certain embodiments of the invention delineated it is to be understood that structural changes may be made without departing from the spirit and scope of the invention.

What I claim is:

1. In a smelting furnace, vertical retorts and a charging car movable over the top thereof which is provided with at least one plunger for controlling the volume of the charge fed from the car and means for moving said plunger.
2. A smelting furnace including a plurality of retorts, means movable over the top of the retorts for charging said retorts, and means for coupling the charging means to the retort to prevent the escape of vapors from said retorts.
3. In a smelting furnace a plurality of retorts, means for forcing the charge into said retorts, and means for coupling the charging means to the retort to prevent the escape of vapors from the retorts during the charging operation.
4. In a smelting furnace a plurality of re-

torts, means movable over the top of said retorts of sufficient carrying capacity to charge a plurality of retorts, means for feeding a predetermined quantity of material into each of the several retorts and means for coupling the charging means with the retorts to prevent the escape of vapors therefrom.

5. In a smelting furnace the combination of a tapered vertical retort, means for forcing the charge into the retort, means for preventing the escape of gases during the feeding operation, means for loosening the slag and residue in the bottom of the retort and means for discharging said slag and residue from the retort.

6. A smelting furnace including a vertical retort and a slag breaker having radial arms with horizontal cutting edges formed thereon, and vertical cutting blades formed at the extremities of said radial arms, for disintegrating and breaking the slag loose from the interior of the retort.

7. In a smelting furnace a slag breaker having arms with substantially horizontal cutting edges formed thereon and substantially vertical cutting blades formed at the extremities of said arms.

In witness whereof, I have hereunto signed my name.

FERD FIECHTL.
